INVENTOR

UNITED STATES PATENT OFFICE

117,613

DESIGN FOR A TEXTILE FABRIC

Edward L. Espen, Elkins Park, Pa.

Application August 25, 1939, Serial No. 86,885

Term of patent 3½ years

To all whom it may concern:

Be it known that I, Edward L. Espen, a citizen of the United States, residing at Elkins Park, in the county of Montgomery and State of Pennsylvania, have invented a new, original, and ornamental Design for a Textile Fabric, of which the following is a specification, reference being had to the accompanying drawing, forming part thereof:

The figure represents a plan view of the fabric embodying the design.

I claim:

The ornamental design for a textile fabric, as shown.

EDWARD L. ESPEN.
